UNITED STATES PATENT OFFICE

TITO PRINCIPESSA AND JOHN DE COSIMO, OF ELLWOOD CITY, PENNSYLVANIA

HOT OR COLD AIR HOME CLOTHES DRYING MACHINE

Application filed March 3, 1931. Serial No. 519,782.

The invention primarily has for its object to provide a simple, inexpensive clothes dryer which is portable, will occupy but little space when not in use, and one which may take a 5 large spread of clothes to be dried.

Further, it is an object to provide such a clothes dryer as is electrically operated to cause a blast of air, either hot or cold, to flow against the clothes whereby they are dried 10 and by which blast they are rotated, the construction being such as to effect an equal distribution of air to all of the garments.

Further, it is an object to provide an apparatus of the character stated of a height 15 and construction so that the clothes may be hung up from a single standing point.

Further, it is an object to provide a drying machine which will afford facilities for quickly drying the washing within a limited 20 space inside the house regardless of outside weather conditions.

Further, it is an object of the invention to provide a drying machine, the clothes carrier 25 of which may be taken down and the whole apparatus stored in a closet or other out of the way place when not being used.

Further, it is an object of the invention to provide a drying rack of such construction that the large pieces of clothes may be 30 hung in a circle to embrace the smaller garments hung within the confines of the circle, the larger pieces serving to partially enclose the air stream and prevent its spread before it has acted upon the garments.

Other objects will in part be obvious and 35 in part be pointed out hereinafter.

To the attainment of the aforesaid objects and ends, the invention still further resides in the novel details of construction, combination 40 and arrangement of parts, all of which will be first fully described in the following detailed description, then be particularly pointed out in the appended claims, reference being had to the accompanying drawing, in 45 which:-

Figure 1 is an elevation, parts being broken away and shown in section illustrating the machine ready to use.

Figure 2 is a plan view of the base unit, 50 parts being broken away.

Figure 3 is a plan of the rotating rods and ring.

Figure 4 is an enlarged detail sectional view of a portion of the apparatus.

In the drawing, in which like numerals and 55 letters of reference indicate like parts in all of the figures, 1 represents a ring or rim having suitable spokes 1a which are secured to a central hub 1b that is socketed to fit the upward projection 4a of a disk 4, the latter 60 having threaded apertures in its periphery to receive the clothes hanging rods 2 which radiate from the disk. These rods are readily removable and only such number need be used 65 at a time as may be required by the number of garments to be dried at the time.

The disk 4 has a recessed bearing socket 4b so designed as to fit over the upper end 70 of the center post 5, and in order that it may turn freely on the post a bearing ball 3 is located within the socket 4b on the end of the post as shown in Figure 1.

The post 5 is preferably tubular at least at its lower end to fit onto a spindle 6a which projects up from a flange plate 6 that is centrally located on the top of the drum-like 75 base unit.

The base unit is a drum-like structure composed of a bottom including a T-iron hoop 20, a pair of substantially parallel diametrically crossed straps 17-17 bolted to the hoop 20 as at 17a, there being a plate, preferably of sheet iron, provided as a floor. Casters 19 have their shanks held in sockets 80 in the T-iron rim 20 by screw bolts 18 and 85 serve to support the unit portably.

Centered on the plate 20b and secured to the crossed straps 17 by removable clamps 13 and bolts 9 is an electric motor 14 whose shaft is mounted vertically, and carries a 90 fan 15 to create an upward blast of air around the post 5.

Secured to the hoop 20 are uprights 11 to which the crossed strips 21 are bolted as 95 at 9. Fastened at 10 to certain of the uprights 11 are electric sockets 16 fitted with heating units 12 which are wired to a suitable source of electric energy (not shown) in a separate sub-circuit from that containing the motor so that the heaters may be used 100

independently of the motor, i. e. may be turned on or off while the motor is in action as desired.

5 The periphery and top of the drum-shaped base unit is formed by wire mesh 7 constituting an enclosure as shown, the fan, motor and heaters being located within the enclosure.

10 In using the apparatus the clothes to be dried are suspended on the ring 1. The fan is turned on and an upward current of air is established, either hot or cold, accordingly as the heating units are energized or not. This causes the disk 4 and rods 2 and ring 1

15 with the clothes to rotate through the action of the air current, carrying the clothes around the axis of the post 5 on the ball bearing 3. The air current further causes the clothes to flutter, thus driving the moisture out of the

20 clothes at the top.

The larger clothes, such as sheets, being hung on the ring 1 form an annular wall around the clothes on the rod 2 and in a measure confine the air stream to action as 25 a more or less dense current, preventing its spreading laterally until it has acted effectively on all of the clothes on the dryer.

30 From the foregoing description, taken in connection with the accompanying drawing, it is thought the complete construction, operation, and advantages of my invention will be clear to those skilled in the art to which it relates..

35 What we claim is:

1. In clothes dryers, a drum-like base unit having foraminous peripheral and top walls, a post mounted on the top of the base unit and extending vertically upwardly therefrom, an electric motor driven fan within 40 the drum-like base for causing movement of an air stream upwardly around said post, a disk having radial arms rotatably mounted on the upper end of said post, and a ring with spokes and hub mounted on said disk.

45 2. In a clothes dryer, a drum like base unit, having foraminous peripheral and top walls, a post mounted on the top of the base unit and extending vertically upwardly therefrom, an electric motor driven fan within 50 the drum-like base for causing movement of an air stream upwardly around said post, a disk having radial arms rotatably mounted on the upper end of said post, and a ring with spokes and hub rotatably mounted on said disk.

55 3. In clothes dryers, a drum-like base unit having a foraminous peripheral and top walls, a post mounted on the top of the base unit and extending vertically upwardly 60 therefrom, an electric motor driven fan within the drum-like base for causing movement of an air stream upwardly around said post, a disk having radial arms rotatably mounted on the upper end of said post, and a ring with 65 spokes and hub mounted on said disk, said

ring being of greater radius than the length of said arms.

4. In clothes dryers, a drum-like base unit having foraminous peripheral and top walls, a post mounted on the top of the base unit and extending vertically upwardly therefrom, an electric motor driven fan within the drum-like base for causing movement of an air stream upwardly around said post, a disk having radial arms rotatably mounted on the upper end of said post, and a ring with spokes and hub mounted on said disk, and means within the drum-like base for heating the air delivered to the fan.

75 5. In clothes dryers, a drum-like base unit having foraminous peripheral and top walls, a post mounted on the top of the base unit and extending vertically upwardly therefrom, an electric motor driven fan within the drum-like base for causing movement of an air stream upwardly around said post, a disk having radial arms rotatably mounted on the upper end of said post, and a ring with spokes and hub rotatably mounted on said disk, and means within the drum-like base for heating 80 the air delivered to the fan.

85 6. In clothes dryers, a drum-like base unit having foraminous peripheral and top walls, a post mounted on the top of the base unit and extending vertically upwardly therefrom, an electric motor driven fan within the drum-like base for causing movement of an air stream upwardly around said post, a disk having radial arms rotatably mounted on the upper end of said post, and a ring with 95 spokes and hub mounted on said disk, said ring being of greater radius than the length of said arms, and means within the drum-like base for heating the air delivered to the fan.

100 7. In clothes dryers, a drum-like base unit having foraminous peripheral and top walls, a post mounted on the top of the base unit and extending vertically upwardly therefrom, an electric motor driven fan within the drum-like base for causing movement of an air stream upwardly around said post, a disk having radial arms rotatably mounted on the upper end of said post, and a ring with 110 spokes and hub mounted on said disk, said post being mounted on said drum-like base by a quick detachable joint and said disk and said hub being freely detachable from one 115 another from said post.
